CAR COUPLER

Arthur J. Bazeley, Shaker Heights, Ohio, assignor
to National Malleable and Steel Castings Com-
pany, Cleveland, Ohio, a corporation of Ohio

Application March 28, 1936, Serial No. 71,414

19 Claims. (Cl. 213—127)

This invention relates to car couplers and more particularly a coupler of the bottom operative type in which a rotor lever is pivoted to the bottom of the coupler and operatively connected to the lock by means of a link.

One object of my invention is the provision of means for operating the knuckle thrower, which means are pivoted on the guard arm side of the lock, whereby the contact between the 10 knuckle thrower and the thrower operating means is positioned a maximum distance from the pivot point of the knuckle thrower. In addition, I provide means for supporting and guiding the knuckle thrower during its movements so as 15 to assure an adequate lockset as well as smoother and more positive operation of the knuckle thrower.

A still further object of my invention comprises anti-creep means between the lock and 20 coupler head to limit undesired upward movement of the lock. My invention also contemplates means for positively disengaging the anti-creep in all locked positions of the lock, even though the anti-creep shoulder on the lock is in 25 contact with the anti-creep lug on the coupler.

Other objects and advantages of the invention will be in part apparent and part described in conjunction with the following drawings, in which:

30. Figure 1 is a vertical longitudinal sectional view of a car coupler embodying my invention showing the parts in locked position.

Figure 2 is a transverse section through the coupler taken on line 2—2 of Fig. 1 with the 35 knuckle omitted.

Figure 3 is a partial view similar to Fig. 1 showing the anti-creep disengaged.

Figure 4 is a view similar to Fig. 3 with the lock in lockset position.

40. Figure 5 is a view similar to Fig. 3 showing the position of the parts at the beginning of knuckle throw and with a section of the knuckle thrower taken on line 5—5 of Fig. 9.

Figure 6 is a view similar to Fig. 5 at the end 45 of knuckle throw.

Figure 7 is similar to Fig. 3 and shows the lock in engagement with the anti-creep lug.

Figure 8 is a view similar to Fig. 7 showing the lock disengaged from the anti-creep.

50. Figure 9 is a horizontal sectional view taken on line 9—9 of Fig. 1.

Figure 10 is a vertical sectional view of a modification of my invention, and

55. Figure 11 is a partial view similar to Fig. 10 with the anti-creep disengaged.

Figure 12 is a vertical sectional view showing a modification.

Referring to the drawings, there is shown in Fig. 1 a coupler having the usual pivoted knuckle 1, a vertically movable lock 2, and a knuckle thrower 3. The leg 4 of the lock normally extends downwardly into an opening 5 in the bottom of the coupler. At its lower end the lock leg is made narrower to form a downwardly extending projection 6 on the knuckle side of the lock. The rear side of the lock adjacent the projection 6 is formed with a seat 7 which is adapted to rest on the knuckle thrower when the lock is in lockset position. Extending laterally from the lower end of the lock is a trunnion 8 adapted to enter a slot 9 in the lifter link 10. This link is formed with an enlarged upper portion 11 substantially filling the opening 5 in a longitudinal direction.

The rear surface 12 of the head portion may 20 preferably engage the rear wall 13 of opening 5 and some clearance, as shown at 14, may be provided between the forward surface 15 of the link and the front wall 16 of the opening 5. The link may be made narrower at its lower portion and 25 is provided with a laterally offset arm 17. Between the arm 17 and the lower end 18 of the link there is received one end 19 of a rotor lifter lever 20. The link and lever may be pivotally connected as by a rivet 20'. The other end of 30 lever 20 is formed with a hook-portion 21, which is pivoted on a trunnion 22 integral with the coupler.

In Fig. 1 I have shown the usual uncoupling rod and bail type of operating mechanism for 35 the coupler, although it is obvious that other types can be used if desired. In the form illustrated, the lever 20 is provided intermediate its ends with an opening 23 for receiving the hooked end 24 of the element 25.

40. The opposite end of element 25 is formed with an elongated slot 26 for receiving a bail 27. The bail is operated from the side of the car by means of the usual uncoupling rod 28.

In order to limit creeping of the lock upwardly 45 to such an extent as would unlock the knuckle, I provide a lug 29 extending into the forward part of opening 5. At the lower end of the portion 6 of the lock is a forwardly extending foot 30 normally underlying the projection 29. It 50 will be clearly seen from Fig. 1 that with the upper portion 11 of the link 10 substantially filling the opening 5 in a longitudinal direction and the slot and projection engagement between the lock and link, the lock cannot move rearwardly 55

a sufficient amount to withdraw the foot from beneath the anti-creep lug. However, upon operation of the uncoupling rod, the lever 20 moves upwardly causing the lower surface of slot 9 in the link element to engage the trunnion 8 and act as a cam to withdraw the lower end of the lock and hence the foot 30 from beneath the anti-creep lug. The link 10 during this operation may slide forwardly until its surface 15 engages the forward wall 16. However, as soon as the lower end 31 of slot 9 engages the trunnion 8 further movement will cause the toggle between the lock, link and rotor lever to break rearwardly so that the link 10 will engage the rear wall 13 of the opening, as shown in Fig. 3.

Further movement of the parts upwardly will cause the lock to be placed in lockset position, as shown in Fig. 4, at which time the seat 7 rests upon the end 32 of the knuckle thrower. In Fig. 2 there is shown a transverse vertical section through the coupler head with the parts in locked position. It will be noted from Figs. 2 and 9 that the coupler is provided with a curved recess 33 for receiving the extension 34 of the knuckle thrower. Normally, the thrower rests on the bottom of this recess so that when the lock is in lockset position its weight resting on the thrower will not cause the latter to tip. In previous constructions this tipping of the thrower provided only a small area of contact between the lock and thrower on the knuckle side of the lock. By my improved construction a lockset engagement between the lock and thrower is obtained throughout the lateral extent of the lockset seat on the lock. Furthermore, there has at times been a tendency, when the lock is raised, for the knuckle thrower to move upwardly because of the frictional engagement between the thrower and the rear of the lock. This sometimes caused the thrower to be lifted until its trunnion 35 was raised partially out of the trunnion opening in the coupler head. It is apparent that a proper lockset cannot be obtained with the thrower thus raised. In addition, it would seriously interfere with the knuckle throwing operation. It will be appreciated that by providing the projection and recess engagement between the end of the knuckle thrower and coupler there can be no substantial upward movement of the knuckle thrower such as would lead to the above described difficulties.

In Fig. 5 the parts have been moved upwardly until the pivot 36 of the lock has engaged the ledge 37 in the forward part of the coupler. At this time the rear surface 12 of the link is in engagement with the knuckle thrower. In Fig. 6 the parts are shown at the end of the knuckle throw and it will be noted that the pivot 36 is no longer in engagement with the ledge 37 but instead the forward upper surface 38 of the lock has engaged the upper wall 39 of the coupler, and forms a pivot for the lock during the latter portion of knuckle throw. This transfer of pivot points takes place between the beginning and end of knuckle throw. By the use of the two pivot points I provide means for decreasing the amount of slip between the link 10 and the knuckle thrower. If all of the pivotal movement of the lock were obtained about pivot 36, the lock leg and consequently the link 10 would have had to move a greater distance upwardly in order to obtain the same amount of movement of the knuckle thrower. It is, of course, desirable to limit the relative movement between the link and thrower as much as possible, since the less the friction

between these parts the greater will be the amount of work available for throwing the knuckle. After the knuckle is closed, the lock, link and rotor lever will, of course, assume their normal positions in the usual manner.

In Fig. 7 the lock is shown moved upwardly in engagement with the anti-creep ledge. This condition may occur in service due to relative movement between the lock and knuckle tail. In this view the rotor lever 20 and the link 10 have been moved upwardly until the surface 15 on the link is in engagement with a cam surface 40 adjacent the anti-creep lug. Further movement of the link 10 upwardly by operation of uncoupling rod 28, will cause the engagement between the slot 9 and trunnion 8 to force the lower end of the lock leg rearwardly to disengage the anti-creep. At the same time the link will be moved rearwardly by the cam surface 40. The total movement of the lock leg rearwardly due to action of the cam surface 40 on the link and the trunnion and slot engagement between the link and lock will be sufficient to move the foot 30 from beneath the anti-creep ledge, as shown in Fig. 8. Link 10 may also engage surface 40 when the lock is in a lower position than is shown in Fig. 7. This will occur if for any reason the toggle between the lock and link does not readily break to the rear and will result in link 10 moving upwardly during operation of the uncoupling rod, until it engages forward wall 16 or surface 40, after which the lock will be withdrawn from beneath lug 29 in the same manner as previously described. If desired, the cam surface 40 can be omitted and the slot 9 made longer, as shown in Fig. 12, so that the same amount of rearward movement of the lock can be obtained by the camming action of the slot and trunnion alone.

In Figs. 10 and 11 I have shown a slight modification of my invention in which the link 41 is provided with a downwardly and rearwardly extending projection 42 lying beneath a surface 43 on the coupler. The lock is provided with a trunnion 46 extending into a slot 44 in link 41 similar to the slot and trunnion engagement shown in the preferred form except it will be noted that the trunnion 46 is located adjacent the rear surface of the lock. The engagement between projection 42 and surface 43 forms an anti-creep to limit upward movement of the lock. In order to preclude undesired disengagement of the anti-creep, the slot 44 is provided with an inward projection 45 partially surrounding the trunnion 46. Since the leg of the lock in the modification is shown in engagement with the forward wall of the opening in the coupler, it will be seen that forward movement of link 41 is normally prevented. However, when it is desired to lift the lock, the rotor lever 20 will move the link first upwardly to remove projection 45 from behind the trunnion 46 and then forwardly and upwardly so that the trunnion 46 on the lock lies in the lower end of the slot, as shown in Fig. 11. In this position, it will be seen that the link has been withdrawn from beneath the surface 43. Further movement of the parts upwardly will cause the lock to be placed in lockset position, or, if desired, the knuckle can be thrown in the same manner as described in connection with the preferred form of the invention.

The terms and expressions which I have employed are used as terms of description and not of limitation, and I have no intention, in the use of such terms and expressions, of excluding any equivalents of the features shown and de-

scribed or portions thereof, but recognize that various modifications are possible within the scope of the invention claimed.

What I claim is:

- 5 1. In a car coupler, a vertically movable lock having a downwardly extending leg, a rotor lift lever pivotally mounted on said coupler to the rear of said lock, a link connecting said lever and the leg of said lock, disengageable anti-creep 10 means comprising a projection on said leg underlying a stop on said head and means normally preventing disengagement of said anti-creep means.
- 15 2. In a car coupler, a vertically movable lock having a downwardly extending leg, a rotor lift lever pivotally mounted on the bottom of said coupler to the rear of said lock, a link connecting said lever and the leg of said lock, said connection between said link and leg being adapted 20 to prevent rearward movement of said leg relative to said link when said lock is in locked position, anti-creep means comprising a projection on said lock underlying a stop on said head and means limiting rearward movement of said link when said parts are in locked position.
- 25 3. In a car coupler, a lock having a leg extending downwardly into an opening in said coupler, a lever pivoted on said coupler to the rear of said opening, a link connecting said lever and lock, a 30 lug on said coupler extending into said opening and adapted to cooperate with a portion of said lock to limit upward movement thereof, said link having an upper portion substantially filling said opening in a direction longitudinally of said coupler.
- 35 4. In a car coupler, a lock having a leg extending downwardly into an opening in said coupler, a lever pivoted on said coupler to the rear of said opening, a link connecting said lever and lock, a 40 lug on said coupler extending into said opening and adapted to cooperate with a portion of said lock to limit upward movement thereof, said link having an upper portion substantially filling said opening in a direction longitudinally of said coupler, said connection comprising camming 45 means for effecting withdrawal of said lock from beneath said lug.
5. In a car coupler, a lock, a lever pivoted on said coupler, a link pivotally connected at one 50 end to said lever and extending upwardly adjacent said lock and being formed at its upper end with a forwardly and upwardly extending slot, said lock having a projection extending into said slot, said slot and projection engagement being adapted upon upward movement of said lever, to 55 lift said lock to unlocked position, anti-creep means between said lock and coupler, and means including said slot and projection for effecting disengagement of said anti-creep means.
6. In a car coupler, a knuckle and a lock, a 60 knuckle thrower pivoted for movement in a horizontal plane, lock operating means pivoted to the bottom of said coupler, an element extending upwardly through an opening in said coupler and 65 operatively connecting said means and said lock, said element being adapted to engage said knuckle thrower and to move the same about its pivot to open the knuckle.
7. In a car coupler, a knuckle and a vertically 70 movable lock, a knuckle thrower mounted to pivot in a horizontal plane, lock operating means pivoted to said coupler, an element pivotally connected to said means and said lock, and means on said element adapted to move said thrower to

knuckle thrown position after vertical movement of said lock to unlocked position.

8. In a car coupler, a knuckle and a lock, a knuckle thrower pivoted intermediate its ends and adapted to rotate in a horizontal plane, lock 5 operating means pivoted to said coupler for rotation in a vertical plane, an element operatively connecting said lock operating means and lock, said element being adapted to engage an end of said knuckle thrower and move the same to 10 knuckle thrown position.

9. In a car coupler, a knuckle and a lock element, a knuckle thrower, lock operating means pivoted to said coupler below said lock, a lifter 15 element connecting the bottom of said lock element and said means and adapted to engage said knuckle thrower and move the same to knuckle thrown position and means on one of said elements adapted to engage said coupler to limit upward movement of said lock when the latter 20 is in locked position.

10. In a car coupler including a knuckle and a lock, a rotor lift lever pivotally mounted on the bottom of said coupler to the rear of said lock, a slotted link connecting said lever and the bottom 25 of said lock, said lock having a projection extending into the slot in said link, said link underlying a portion of said coupler to form an anti-creep and means limiting longitudinal movement of said lock and link when in locked position.

11. In a car coupler including a knuckle and a knuckle thrower, a lock for said knuckle adapted to move vertically and swing rearwardly, means including said lock for actuating said thrower to open said knuckle, said coupler having 30 a plurality of pivot points for said lock and said lock being adapted to successively engage said points during throwing of said knuckle.

12. In a car coupler including a knuckle and a knuckle thrower, a lock adapted to pivot upon 40 opening of said knuckle, lock operating means pivoted on said coupler and a link connecting said operating means and lock, means comprising said link and lock for actuating said thrower to open said knuckle, said coupler and lock being 45 so constructed and arranged that during throwing of said knuckle said lock is successively pivoted about spaced points on said coupler.

13. In a car coupler including a knuckle and a lock element, a rotor lift lever pivotally mounted 50 on the bottom of said coupler to the rear of said lock, a slotted link element connecting said lever and lock, said lock having a projection extending into the slot in said link, one of said elements having a portion underlying a portion of said 55 coupler to the rear of said lock to form an anti-creep and means limiting longitudinal movement of said lock and link when in locked position.

14. In a car coupler, a vertically movable lock element, a lever pivotally mounted on the bottom 60 of said coupler to the rear of said lock, a link element connected to said lever and having a forwardly and upwardly extending slot therein receiving a projection on the bottom of said lock, said slot and projection forming the sole connection between said link and lock, disengageable 65 anti-creep means for said lock comprising a lug on said coupler engageable by a portion of one of said elements during vertical movement thereof, and means normally preventing disengagement of 70 said anti-creep means.

15. In a car coupler, a vertically movable lock element, a lever pivotally mounted on said coupler, a link element connected to said lever and having a forwardly and upwardly extending slot 75

therein receiving a projection on the bottom of said lock, disengageable anti-creep means for said lock comprising a lug on said coupler engageable by a portion of one of said elements during vertical movement thereof, and means normally preventing disengagement of said anti-creep means, the last mentioned means comprising a portion of the other of said elements engageable with a portion of the coupler head.

10 16. In a car coupler, a knuckle and a vertically movable lock, a knuckle thrower pivoted intermediate its ends for movement in a horizontal plane, one end of said thrower being engageable with said knuckle to open the same and the other end of said thrower being in slidable engagement with said lock during vertical movements thereof, and a recess in said coupler receiving a portion of said knuckle thrower at a distance from the pivot thereof for limiting upward vertical movement of said thrower and adapted to maintain said thrower in a horizontal plane.

17. In a car coupler having a pivoted knuckle, a lock element for said knuckle adapted to move vertically and swing longitudinally of the coupler and having a leg portion extending downwardly and forwardly from the knuckle side thereof and normally lying adjacent the forward wall of an opening in the bottom of said coupler, a lever 25 pivotally mounted on said coupler to the rear of said opening, a link element pivotally connected at its lower end to said lever and at its upper end to said portion of said lock, said lever and link being constructed and arranged to lift 30 said lock and swing the same rearwardly during unlocking movements thereof, the upper end of said link element extending rearwardly of

said portion and, when said parts are in locked position, substantially filling said opening longitudinally of the coupler to the rear of said lock, and means on one of said elements adapted to engage a portion of said coupler to limit upward movement of said lock element, the other of said elements being adapted to engage an adjacent wall of said opening to limit movement of said means from beneath said portion of the coupler.

18. In a car coupler, a knuckle, a vertically movable and rearwardly swingable lock, a knuckle thrower pivoted intermediate its ends for movement in a horizontal plane, means directing a rearward and upward force against said thrower for actuating the same, one end of said thrower being engageable with said knuckle to open the same and the other end of said thrower extending to the rear of said lock and adapted to be engaged by said means during said vertical and swinging movements, and means above said other end of said knuckle thrower to resist vertical movement thereof resulting from said upward force.

19. In a car coupler, a knuckle, a vertically movable and rearwardly swingable lock, a 25 knuckle thrower pivoted intermediate its ends for movement in a horizontal plane, means directing a rearward and upward force against said thrower for actuating the same, one end of said thrower being engageable with said knuckle to 30 open the same and the other end of said thrower extending to the rear of said lock and adapted to be engaged by said means during said vertical and swinging movements and means adjacent said other end of said knuckle thrower to limit 35 upward movement thereof.

ARTHUR J. BAZELEY.
